Primary Examiner — Marianne Pandozzi(74) *Attorney, Agent, or Firm* — Polson Intellectual Property Law, PC; Margaret Polson(57) **CLAIM**

The ornamental design for a cold brew filter basket, as shown and described.

DESCRIPTION

FIG. 1 is a top perspective view of a cold brew filter basket showing our new design;

FIG. 2 is a bottom perspective view thereof;

FIG. 3 is a side view thereof, the opposite side being a mirror image thereof;

FIG. 4 is a front view thereof, the rear view being a mirror image;

FIG. 5 is a top plan view thereof; and,

FIG. 6 is a bottom plan view thereof.

The broken lines in the drawing depict portions of the cold brew filter basket that form no part of the claimed design.

1 Claim, 3 Drawing Sheets(56)
